PRESSURE RELIEF MEANS FOR PUMP
 Ralph E. Henry, Rixford, Pa., assignor to Dresser Industries, Inc., Dallas, Tex., a corporation of Delaware
 Filed Dec. 6, 1961, Ser. No. 157,438
 4 Claims. (Cl. 103—42)

This invention relates to pressure relief means for a pump, and more particularly to pressure relief valve means for a hydraulic pump of the positive displacement type.

With a hydraulic pump of the positive displacement type such as a gear pump, the pressure in the outlet of the pump varies or pulses in response to the quantities or surges of the fluid positively displaced by the pump. These variations or pulsations in the pump outlet and the outlet line connected thereto cause the normal type of relief valve to chatter or oscillate rapidly and this chattering not only produces undesirable noise but also disturbs the pressure of the fluid throughout the hydraulic system connected to the pump outlet, setting up vibrations that may even break pipes.

The main object of the present invention is to provide in a pump pressure relief means which do not chatter and dampen or filter out vibrations.

Another object of the invention is to provide such pressure relief means which are adjustable so that the pressure level at which the relief means operates can be varied selectively.

Other objects of the invention are to provide such pressure relief means which are simple in construction, relatively inexpensive to incorporate in a pump, and not likely to get out of order or require repair.

Still other objects and advantages of the invention will be apparent from the following detailed description of a preferred embodiment thereof which is illustrated in the accompanying drawings wherein:

FIG. 1 is a vertical central section through a gear pump equipped with pressure relief valve means constructed in accordance with the principles of the present invention, and showing the valve in a closed or seated position.

FIG. 2 is an enlarged sectional view of the pressure relief valve means shown in FIG. 1 but illustrating the valve in an open or unseated position, and further showing only a fragmentary part of the pump body.

The numeral 10 represents generally the body of a gear pump suitably formed with a lower curved wall 8 and an upper inner curved wall 9 to provide chambers for a pair of cooperating gears 13 and 14, and also formed to provide an inlet 11 and an outlet 12. Suitable means (not shown) cause rotation of one of the gears 13 and 14 which in cooperation with the walls 8 and 9 operate to displace positively fluid from the inlet 11 to the outlet 12.

In accordance with the present invention, means are provided to relieve pressure in the outlet 12 should it rise above a predetermined level. For this purpose, an outer wall 15 is spaced from the upper inner curved wall 9 of the pump body to provide a passage 16 which at one end communicates with the outlet 12 and at its other end communicates with a cylindrical hole 18 of reduced diameter. The other end of this hole 18 is shown as communicating via the passage 19 with the inlet 11. The passage 19 is formed preferably as shown by an outer wall 20 and a valve housing portion 17 intermediate the walls 15 and 20. These walls 15 and 20 and portion 17 are preferably formed integrally with the pump body 10. The passages 16, 18 and 19 jointly provide a bypass connecting the pump inlet and outlet.

The pump body on the downstream side of the hole 18 is formed with a cylindrical counterbore as indicated

2

at 21 to provide an annular seat 22 which faces toward the pump inlet 11.

Movable valve means are operatively associated with the seat 22. Such valve means are shown as including a cylindrical sleeve member 23 slidably arranged within a bore 24 provided in the pump body portion 17 so that one end of this sleeve opposes the seat 22. Preferably the inner and outer corners of the sleeve member 23 at this end are bevelled or chamfered to provide a relatively narrow annular end face 25 which is adapted to engage abuttingly the opposing annular seat 22.

Intermediate its ends, the sleeve member 23 is shown as provided with an internal wall 26 which extends transversely of the member. This wall is shown as having a central through hole 28 provided with an annular groove to receive an O-ring 29. The O-ring 29 sealingly embraces a cylindrical stem 30. One end of the stem 30 carries a piston 31 which is relatively slidably arranged within the sleeve member 23 and is located between the transverse wall 26 and the seat 22. The space between the piston 31 and transverse wall 26 provides a chamber 32. The piston 31 is shown as having a restricted opening 33 extending therethrough which establishes communication between the chamber 32 and the bypass channel constituted by the passage portions 16, 18 and 19.

Any suitable means may be provided for securing the piston 31 to the stem. As shown, the piston is removably connected to the stem and for this purpose the stem 30 is shown as having a coaxially projecting neck 34 of reduced diameter so as to provide a forwardly facing annular shoulder 35 against which the inner face 36 of the piston 31 bears adjacent a central hole 38 provided in the piston. The outer end of the reduced neck 34 is externally threaded to receive a nut 39 which bears against the outer end face 40 of the piston 31. Tightening the nut 39 clamps the piston 31 against the shoulder 35.

The other end of the stem 30 is shown as secured to a generally cup-shaped plug 41 having an annular wall portion 42 provided with external threads 43 adapted to be screwed into an internally threaded hole 44 provided in the pump body. The hole 44 is coaxial and communicates with the bore 24 for the slide valve member 23. The adjusted position of the plug 41 relative to the pump body may be maintained by a lock nut 45 which is threaded on the threads 43 and bears against an outer end face 37 of the pump body portion 17. The outer end portion of the plug 41 is shown as being enlarged and provided with an out-of-round perimetrical configuration to permit the application of a wrench or the like (not shown) to enable the plug to be rotated.

The adjacent end of the stem 30 is shown as having a reduced neck 46, leaving an outwardly facing shoulder 47 which engages the inner face 57 of the end wall of the plug 41. The outer end portion of the neck 46 is externally threaded as indicated at 48. The neck 46 extends through a counterbored hole 49 provided in the end wall of the plug 41. This counterbored hole provides an outwardly facing shoulder 50 against which the inner end face of a nut 51 screwed onto the threaded portion 48 bears. Tightening the nut 51 clamps the stem shoulder 47 against the plug face 57.

A helical compression spring 52 is shown as operatively interposed between the plug 41 and sleeve member 23 so as to urge the latter toward the seat 22. Specifically, one end of the spring 52 bears against one side of the transverse wall 26 and the other end of this spring bears against the inner face 57 of the plug 41.

It will be seen that the preload on the spring 52 can be varied by adjusting the axial position of the plug 41 relative to the pump body portion 17. Thus by screwing the

plug 41 into the body the preload on the spring 52 is increased, whereas backing off or unscrewing the plug 41 partway reduces the preload on the spring. Before making any adjustment of the plug 41, the lock nut 45 is suitably loosened and then following this adjustment the lock nut is retightened.

The adjustable plug 41 and lock nut 45 are shown as covered by a removable cap 53 having attaching flanges 54 opposing the body end face 37. A gasket 55 is shown as interposed between the flanges 54 and this face 37. Removable machine screws 56 pass through holes in the attaching flanges 54 and are received in threaded recesses provided in the pump body.

The space between the sleeve member 23 and plug 41 which may vary in volume due to movement of the sleeve member relative to the stationary plug, is connected to the passage portion 19 by the lateral branch passage 58 formed in the body portion 17 and which intercepts the bore 24 and hole 44.

From the foregoing, it will be seen that the piston 31 acts as a fixed wall element spaced from the seat 22, the face 40 of which is constantly exposed to the pressure in the pump outlet 12. Also, the sleeve member 23 acts as a closure member cooperable with the seat 22 and movable with respect to the fixed piston or wall element 31. Another way of viewing these elements is to regard the sleeve member 23 with its transverse wall 26 as a movable cylinder member in which the piston 31 is fixed although slidably relative to the annular wall.

In operation, it will be seen that the pressure in the pump outlet 12 is transmittable to the chamber 32 formed by the opposing and spaced walls 31 and 26 through the restricted opening 33 arranged in the wall member or piston 31 and via the connected passage portions 16 and 18. If the pressure within the chamber 32 is high enough to develop a force directed from left to right as viewed in the figures to overcome the oppositely directed force exerted by the spring 52, this spring will yield and allow the sleeve member 23 to move away from its seat 22, thereby establishing communication between the passage portions 18 and 19 and hence between the pump inlet and outlet. When the force exerted by the fluid pressure within the chamber 32 is inadequate to overcome that exerted by the spring 52, this spring will maintain the sleeve member 23 against the seat 22, as illustrated in FIG. 1.

The purpose of the restricted opening 33 in the wall element or piston 31 is to dampen or filter out the vibrations or pressure fluctuations in the pump outlet 12, while allowing the more or less steady state or mean pressure to be transmitted to the chamber 32. The smaller the transverse area of the restricted opening 33 in the wall element or piston 31 relative to the volume of the chamber 32, the more damping effect produced.

Another purpose of the restricted opening 33 in piston 31 is to act as a metering orifice in restricting the velocity of movement of sleeve 23. In order for sleeve 23 to move, fluid must be displaced through the restricted opening 33. This prevents overcontrolling and consequent pressure surges.

As noted hereinabove, the preloading of the spring 52 is variable by adjusting the plug 41. This adjustment and hence preloading determines the pressure within the by-pass channel at which the pressure relief valve member 23 will open or unseat.

Since variations and modifications of the precise construction of the invention illustrated may occur to those skilled in the art, the scope of the invention is to be measured by the appended claims.

What is claimed is:

1. In a pump including a body having a by-pass con-

necting an inlet and an outlet, the combination therewith of pressure relief means comprising a seat in said by-pass, a fixed piston element spaced from said seat and having two opposite sides one of which is constantly exposed to the pressure in said outlet and also having an opening therethrough connecting said sides, a movable cylinder member having an annular wall slidably arranged on said element and forming jointly therewith a chamber on the other side of said element communicating with said opening, and yielding means urging said member toward said seat, said member when seated blocking said by-pass but when unseated unblocking said by-pass.

2. In a pump including a body having a by-pass connecting an inlet and an outlet, the combination therewith of pressure relief means comprising a seat in said by-pass, movable valve means operatively associated with said seat and including a sleeve and a wall arranged transversely of and within said sleeve, yielding means urging said sleeve toward said seat, said sleeve when seated blocking said by-pass but when unseated unblocking said by-pass, and a fixed piston arranged within said sleeve between said wall and seat to provide a chamber, said piston having an opening therethrough communicating with said chamber.

3. In a pump including a body having a by-pass connecting an inlet and an outlet, the combination therewith of pressure relief means comprising a seat in said by-pass, movable valve means operatively associated with said seat and including a sleeve and a wall arranged transversely of and within said sleeve and having an opening therethrough, yielding means urging said sleeve toward said seat, said sleeve when seated blocking said by-pass but when unseated unblocking said by-pass, a fixed stem extending through said opening and slidably sealed with respect to said wall, and a piston secured to said stem and arranged within said sleeve between said wall and seat to provide a chamber, said piston having an opening therethrough communicating with said chamber.

4. In a pump including a body having a by-pass connecting an inlet and an outlet, the combination therewith of pressure relief means comprising an annular seat surrounding said passage, valve means slidably arranged on said body opposite said seat and including a sleeve having an end adapted to engage said seat and also including a wall arranged transversely of and within said sleeve intermediate the ends thereof said wall having a central opening extending therethrough, a stem slidably extending through said opening, a piston secured to one end of said stem and arranged within said sleeve between said wall and seat to provide a chamber, said piston having an opening therethrough communicating with said chamber, a member adjustably mounted on said body and secured to the other end of said stem, and spring means operatively interposed between said wall and member and having a preload variable by adjustment of said member.
